United States Patent Office.

F. KOPPER, OF NEW YORK, N. Y.

Letters Patent No. 71,022, dated November 19, 1867; antedated November 9, 1867.

IMPROVED TOILET-TABLE.

The Schedule referred to in these Letters Patent and making part of the same.

TO ALL WHOM IT MAY CONCERN:

Be it known that I, F. KOPPER, of the city, county, and State of New York, have invented new and useful Improvements in "Toilet-Stands or Tables;" and I do hereby declare that the following is a full, clear, and exact description thereof, which will enable others skilled in the art to make and use the same, reference being had to the accompanying drawings forming part of this specification.

The present invention relates to improvements in toilet-stands or tables, which consist in so constructing the stand that it can be folded up into a compact shape when not in use, and when in use brought to the proper form to receive and support a foot-bath or a wash-bowl, or any other toilet article, or to be used for any of the ordinary purposes of the toilet. In the accompanying plate of drawings my improvements in toilet-stands or tables are illustrated—

Figure 1 being a central longitudinal vertical section through the stand, in position for being used.

Figure 2, a side view of the same folded up; and

Figure 3 a transverse section in the plane of the line xx , fig. 2.

A, in the drawings, represents my improved toilet-stand or table, which consists of a platform, B, made in two parts or sections hinged together, so that they can be closed, the one upon the other, the hinge being upon the under side. Each section of the platform B is provided with similar supporting-legs C, two in each section, each of which sets of legs is secured to a cross-bar or rail, D, by which they are hinged to the under side of the platform, each rail being provided with a spring-catch, E, by which the legs can be fastened in an upright position for supporting the platform, as shown in fig. 1. F, a towel-frame or rack, hung in one end of platform section, so as to swing thereon, this frame, when the two sections are closed, lying in and between the two, and when opened, or in position for being used, being susceptible of being swung up into an upright position, suitable for use.

I claim as new, and desire to secure by Letters Patent—

The combination of the hinged parts B, bars D, hinged legs C, spring-catch E, and adjustable towel-frame F, constructed and adapted to be folded together, as herein set forth for the purpose specified.

The above specification of my invention signed by me this 22d day of February, A. D. 1867.

FRED. KOPPER.
